UNITED STATES PATENT OFFICE.

GEORG LUDWIG DOERR, OF MANNHEIM, GERMANY, ASSIGNOR TO I. G. FÄRBEININDUSTRIE AKTIENGESELLSCHAFT, OF FRANKFORT-ON-THE-MAIN, GERMANY, A CORPORATION OF GERMANY.

ROLLER FOR CALENDERING MACHINES.

Application filed January 8, 1926. Serial No. 79,965.

This invention relates to a roller for calendering machines, which is particularly useful for smoothing or glazing paper or textile webs and it provides means for obviating deflection at the central portion of the roller.

It is well-known, that rollers of this type are subjected to excessive stress, especially at the center where the greatest strain is applied, and in order to compensate for the deflection the rollers are gradually tapered or slightly convexed from the center to the ends.

An object of the present invention, is to provide a straight non-tapered smoothing roller so that the applied pressure along the entire parallel line of contact between a pair of rollers, when revolving in engagement with each other, is obtained with uniform feeding and smoothing of the web.

Another object of the invention, is to provide a resilient steel tube arranged on a shaft having an enlarged central portion to support the tube, and means for widening the support to accommodate webs of different widths.

The invention resides more particularly in the novel combinations hereinafter described and claimed, reference being made to the accompanying drawing in which:

Fig. 1 is represents a longitudinal section of a roller embodying this invention.

Fig. 2 is a transverse section taken along the line 2 2 of the same.

Fig. 3 is a similar section taken along the line 3 3 of Fig. 1.

In the drawing is shown a shaft having an enlarged cylindrical central member 5 and members 6 of smaller diameter extending from each end of the center as indicated in Fig. 1. The shaft has end members 7 whereby it can be journaled or mounted in the frame of a calendering machine, with another roller of the same type adjacent to it, as is well-known. The enlarged portion of the shaft carries a resilient steel tube 8 which is rigidly fastened thereto by placing it

thereon when hot and allowing it to contract by cooling so as to sweat it to the shaft.

As indicated in the drawing, about one-third of the tube is supported on the enlarged central member, while the other unsupported portions projecting from each end form annular spaces or recesses 9 in conjunction with the reduced ends of the shaft. If greater or smaller possible form changes of the steel tube are required for variable pressures it is effected by inserting onto each end of the reduced portions of the shaft one or a number of steel rings 10 bearing against the shoulders of the central enlargement.

In the use of very wide smoothing rollers, it is difficult to release the calenders when inserting the web to be threaded, and securing the desired smoothing action from the start over the entire width of the operating path cannot be accomplished with tapered rollers, because the meeting faces of the rollers will invariably lightly press against the margins of the web. In the case of two rollers rotating together with straight parallel meeting surfaces, uniform smoothing of the web is obtained over its entire surface under any pressure, because the elasticity or resiliency of the steel tube at its end controls the pressure equalization, and the change of form at each end is regulated by the annular members screwed or otherwise fixed to the reduced portions of the shaft.

I claim:

1. In a roller the combination with a shaft having a central member, of a tube supported on the central member of the shaft, and means for widening the central member of the shaft supporting the tube.

2. In a roller the combination with a shaft having an enlarged member, of a tube supported on the member, and means for widening the member.

3. In a roller the combination with a shaft having a central member of greater diameter, of a tube supported on the member, and means for widening the member.

4. In a roller the combination with a shaft

having a central member of greater diameter, of a resilient tube supported on the member, and means at both ends for widening the member to support more or less of the tube.

5. In a roller the combination with a shaft including a central member having an enlarged diameter and end members of smaller diameter, of a resilient tube supported on the

enlarged member, and rings fixed to the end members made to butt against each end of the central member for supporting more or less of the tube extending beyond the central member.

In testimony whereof I have hereunto set my hand.

GEORG LUDWIG DOERR.
